UNITED STATES PATENT OFFICE.

LOUIS E. VALCOURT, OF PROVIDENCE, RHODE ISLAND, ASSIGNOR TO LOUIS STERN CO., OF PROVIDENCE, RHODE ISLAND, A CORPORATION OF RHODE ISLAND.

CHAIN CONSTRUCTION.

Application filed January 30, 1924. Serial No. 689,532.

To all whom it may concern:

Be it known that I, LOUIS E. VALCOURT, a citizen of the United States, residing at Providence, in the county of Providence and State of Rhode Island, have invented certain new and useful Improvements in Chain Constructions, of which the following is a specification.

This invention relates to improvements 10 in the construction of chains or bracelets formed of a plurality of links; and the object of this invention is the construction of such a chain or bracelet, the links of which telescope one within the other rendering the 15 same extendible in the direction of its length.

A further object of the invention is that both the inner and outer telescoping members of the chain are in somewhat box-shape 20 so that when these members are extended the plain walls only of the inner members are exposed from the front of the chain.

A further object of the invention is to pivotally connect the outer box member 25 with the inner connecting member thereby rendering the chain very flexible.

With these and other objects in view, the invention consists of certain novel features of construction, as will be more fully described, and particularly pointed out in the appended claims.

In the accompanying drawings:

Figure 1 is a side elevation showing a portion of the chain as provided with hooks 35 on its ends for attachment to a wrist watch.

Figure 2 shows one of the outer box-shaped links which is preferably formed of a short section of tubing.

Figure 3 shows the development of one 40 of the inner links as cut from sheet stock with its side edges bent up.

Figure 4 shows the parts of the inner link as folded upon themselves forming a pivot-receiving opening in one end by which 45 it is connected to the next adjacent outer link.

Figure 5 shows a number of the outer box links in section connected together by the inner telescoping links, the whole being 50 slightly extended, the section being taken substantially on line 5—5 of Figure 6, looking in the direction of the arrows.

Figure 6 is a side elevation partly in section of the links shown in Figure 5.

55 Figure 7 is a view showing the top of the

chain with its links extending and exposing the plain surface of the inner telescoping link.

Figure 8 is a view of the under side of the chain showing its links extended and 60 illustrating the cut-away portion of the under side of the inner telescoping links to permit a sliding or telescoping action.

It is found in the practical construction and operation of bracelets of this character 65 of advantage to hinge the different members of the chain or bracelet together so as to render the same flexible; also to construct the links of the chain or bracelet so that when extended only the plain surface of 70 the inner or telescoping link may be exposed thus enhancing the appearance of the bracelet, giving the same a broader surface for ornamentation and at the same time excluding foreign matter from the telescoping parts; and the following is a detailed 75 description of one construction by which these advantageous results may be accomplished:

With reference to the drawings, 10 designates the outer box-shaped link which may be constructed in any suitable way but which is preferably formed from a length of tubing, the same having a pair of ears 11 formed on its side walls at one end 85 thereof and a spur or spring supporting abutment 12 formed on the so-called bottom wall 13 of this tube.

An inner telescoping link 14 is formed preferably of sheet stock as illustrated in 90 Figure 3, also in somewhat of a box-shape, one half of which link is formed with a top wall 15 with shallow side walls 16, the central portion of the bottom wall 17 on the other half being cut away leaving a slot 18 95 between the side arms 19. These arms also have narrow side walls 20 which after being formed are folded over onto the walls 16, in the manner illustrated in Figure 4, thereby providing an inner telescoping, box-shaped link with the middle portion of the bottom wall 17 removed providing an elongated slot or space 18 for the purpose presently described.

At one end of the top wall 15, I have 105 formed a finger 24 which is adapted to extend inwardly and then rearwardly in the manner illustrated in Figure 4, to enter and serve as an abutment for one end of the contracting spring. At the fold 21 of these 110

parts, I have cut away the portion of the side walls as at 22 forming an opening 23 for the reception of the fingers 11 on the next outer link, which fingers are turned 6 inwardly as illustrated in Figure 5, to engage these openings and so hinge these two link members together. The spur or abutment 12 on the lower wall of the outer box-link is turned inwardly to extend through 10 the opening 18 in the inner link and then its extremity 25 is turned inwardly towards the opposite abutment 24 on the inner link and a coiled spring 26 is inserted between these two abutments 12 and 24 to normally 15 cause the inner link to telescope or slide into and be housed in its outer link and bring the adjacent ends of the next outer link into yieldable abutting relation with each other, by which construction it will be seen that 20 only from the front of the chain when the link members are extended is the plain top 15 of the inner telescoping link 14 exposed, and it is only when the chain is reversed or inverted that the slotted portion 18 of this 25 inner link may be seen, as illustrated in Figure 8.

My improved chain or bracelet is of a very practical construction and is very strong and durable and may be made very 30 handsome and attractive in appearance which is especially true owing to the broad exposed surface of the inner links when the chain is extended.

The foregoing description is directed 35 solely towards the construction illustrated, but I desire it to be understood that I reserve the privilege of resorting to all the mechanical changes to which the device is susceptible, the invention being defined and 40 limited only by the terms of the appended claims.

I claim:

1. An extendible bracelet structure comprising a series of outer tubular boxes, sheet 45 metal connecting inner box links therefor each folded upon itself and each of a corre-

sponding shape and size to fit closely and slide in said outer boxes, inwardly-extending hinge fingers on each of said boxes for engaging the folded end of one of said links 50 to hinge said link to said box, and yielding means for connecting the opposite end of said link to the next adjacent box.

2. An extendible structure comprising a series of tubular outer boxes, connecting 55 inner box links having hinge openings therein and telescoping in said outer boxes, inwardly-extending hinge fingers on each of said outer boxes engaging the openings in the next adjacent inner box link for hingedly 60 securing that link to that box, and spring means acting between said inner and outer boxes and links for normally holding said boxes in contracted relation.

3. An extendible bracelet structure comprising a series of tubular members, links telescoping in each of said members and each having an opening in one of its ends and a hook-shaped abutment at its other end, fingers integral with each of said members and located at one end thereof bent into the opening of the link telescoping in the next adjacent member, a hook-shaped abutment on each of said members at the other end thereof, and a spring carried by 75 said link and held between said abutments for causing said member to be normally held in contracted position.

4. An extendible chain structure comprising a series of outer boxes, inner boxes telescoping in each of said outer boxes and having a slot in one of its walls and an abutment at one of its ends, an abutment carried by said outer box extending into and slideable in said slot, means for connecting said 85 inner box to the next adjacent outer box, and a spring acting between said abutments to normally press said boxes into contracted position with a telescopic action.

In testimony whereof I affix my signature.

LOUIS E. VALCOURT.
